UNITED STATES PATENT OFFICE.

BURR B. BLOOD, OF CHICAGO, ILLINOIS, ASSIGNOR, BY MESNE ASSIGNMENTS, TO JEWEL PHONOPARTS COMPANY, OF CHICAGO, ILLINOIS, A CORPORATION OF ILLINOIS.

CASTER.

1,409,150.

Specification of Letters Patent. Patented Mar. 14, 1922.

Application filed July 23, 1919. Serial No. 312,673.

To all whom it may concern:

Be it known that I, BURR B. BLOOD, a citizen of the United States, and a resident of Chicago, in the county of Cook and State of Illinois, have invented certain new and useful Improvements in Casters, of which the following is a description, reference being had to the accompanying drawing, which forms a part of my specification.

10 My invention relates to casters intended to be employed on furniture, more especially on phonograph cabinets and the like; and has for its object the provision of a caster which is adapted to compensate for uneven 15 floors or any slight inaccuracies in the pedestals or legs of the furniture or cabinets and tilting or rocking of the furniture or cabinets thereby prevented; the construction being such that the caster will automatically adjust itself to such uneven conditions as frequently arise in the placing of 20 furniture or cabinets.

The objects and advantages of my improvement will be more readily comprehended from the following description of the drawing, wherein:

25 Figure 1 illustrates my improved caster shown applied to the pedestal or leg of a piece of furniture; the leg and portions of 30 the socket member of the caster being shown in section.

Figure 2 is a perspective view of the cap member or sleeve adapted to receive the upper end of the spindle of the caster.

35 Figure 3 is a perspective view of the upper part of the spindle of the caster.

Figure 4 illustrates a modified form of my invention, portions of which are shown in vertical section, with the caster proper in 40 side elevation.

Figure 5 is a cross sectional view taken on the line 5—5 of Figure 4.

In the particular exemplification of the invention as shown in Figure 1; the wheel or roller indicated at 10 is of the usual construction and rotatably mounted on its axis or pin 11 between the bifurcated portion 12 of the post or spindle 13. The spindle 13 is adapted to extend into the socket member 14 which latter is driven into the leg or supporting portion of the furniture or cabinet and held against rotation or movement. The upper end of the spindle or post 13 is reduced, as more clearly shown in Figure 3, 55 with the reduced portion provided, at an

intermediate point, with a collar 15 so as to provide a cylindrical socket of more or less width intermediate of the lower portion of the spindle or post and said flange 14 for the reception of a lug or pin 16 disposed through 60 the side of the socket member 14. With the lug or pin 16 extending into the cylindrical socket of the spindle or post 13, it is evident that accidental withdrawal of the caster from the socket member will be prevented by 65 the collar 15, but, on the other hand, the caster will have considerable vertical play within the socket member due to the vertical width of the cylindrical socket formed at the reduced end of the spindle or post intermediate of the main portion and said circumferential flange 15.

The upper reduced end of the spindle or post 13 is preferably rounded, as shown in Figures 1 and 3, and is provided with a 75 sleeve or cap 17, shown in detail in Figure 2; the upper end of the sleeve or cap 17 being closed so as to provide suitable bearing for an expansible coil spring 18 arranged in the upper end of the socket member 14 and 80 also permit the caster spindle to rotate in the cap 17. In order that the lower end of the spring may have suitable bearing and not induce a binding relation between the sleeve or cap 17 and the socket member 14, I 85 prefer to provide the plate or washer 19 intermediate of the lower end of the spring and the closed end of the sleeve or cap as shown in Figure 1.

The caster, as illustrated in Figure 1, is 90 shown at its maximum outward position due to the action of spring 18; said maximum position being determined by the projection or lug 16 coming into abutting relation with the circumferential flange 15. The projection 95 16 may be formed and secured in any suitable manner and forced into position after the spindle or post with the cap or sleeve and expansion spring have been properly inserted in the socket member 14.

100 It is evident from the construction shown and described that the caster will readily adjust itself to slight inaccuracies or unevenness, as the spring 18 is under constant compression and tends to force the caster into 105 the maximum distended position shown in Figure 1, so that any teetering or tilting of the furniture or cabinet will be prevented.

In Figures 4 and 5, I illustrate a modified form of my invention wherein a bowed 110

spring 20 is employed instead of the coil spring 18 and adapted to be placed to the exterior of the furniture leg or cabinet pedestal. With this construction, the post or 5 spindle of the caster is formed in the manner shown in Figure 1 and secured within the socket member 14 in the same manner as previously described whereby the accidental withdrawal of the spindle or post is 10 prevented, but vertical play of the spindle permitted to a predetermined extent as in the construction shown in Figure 1. The bowed spring 20 is formed of a strip of properly tempered sheet metal bent into the elliptical 15 or oval form with the integral or continuous side of the strip apertured for the passage of the spindle or post 13, while the ends are bent in opposing direction and preferably cut out or socketed so as to fit about the 20 spindle or post as shown at 21 in Figure 5; where the ends are preferably shown made slightly narrower than the intermediate or main portion of the spring. The continuous side of the spring is preferably disposed 25 on the lower side, namely toward the roller 10, while the split side is adjacent the furniture-leg or socket member 14. It is evident that this construction will permit the caster to have vertical play and will constantly 30 maintain the roller 10 at its normal outward point of movement and therefore in supporting relation with the floor because of the expansible action of the spring.

In practice, merely one or two of the 35 casters of a four legged cabinet or piece of furniture need be of my improved construction, with the improved casters preferably secured to diagonally opposite legs of the furniture, as such arrangement will take 40 care of the unevenness or inaccuracies and will maintain the cabinet or furniture in substantially level position and prevent tilting or swaying of the furniture or cabinet. My improved construction is especially 45 adapted for use in connection with phonograph cabinets where it is essential to have the cabinet in substantially level position in

order that proper operation of the phonograph, through the swinging of the tone-arm, may be obtained.

I have shown and described what I believe to be the simplest and best adaptations of the invention, which, however, is susceptible of embodiment in different form from that disclosed without departing from the spirit of 55 the invention.

What I claim is:—

1. A caster of the class described, comprising a socket member adapted to be inserted into a socket in the element to be supported by the caster, a shank or spindle rotatably mounted in said socket member, means whereby said spindle is permitted longitudinal movement in the socket but held against accidental withdrawal, the outer end of said spindle being provided with a wheel or roller, and a bowed spring formed of sheet metal and apertured for the passage of said shank or spindle, said spring being disposed about the shank or spindle 60 intermediate of the outer end of said socket member and the wheel or roller containing end of said shank or spindle.

2. A caster of the character described, comprising a socket member, a shank or 65 spindle rotatably mounted in said socket member and arranged to have longitudinal movement therein, the outer end of said shank or spindle being bifurcated, a wheel or roller rotatably mounted between said 70 bifurcations, and a strip of resilient metal bent into elliptic or oval form and disposed intermediate of the outer end of said member and the bifurcations of said shank or spindle, with the ends of said strip socketed 75 and disposed about the spindle or shank while the intermediate portion of said strip is apertured for the passage of said shank or spindle.
